MIHRAN M. DOLMAGE, OF WASHINGTON, DISTRICT OF COLUMBIA

NEGATIVE INDUCTANCE

Application filed October 4, 1928. Serial No. 310,395.

This invention relates to a new combination in the electrical art, a negative inductance.

Where, in an electrical circuit or a transmission line, a single frequency alternating current is involved, it is well known that the opposition offered to the flow of electrical currents by an inductance in the electrical circuit or in the transmission line may be offset by a capacity. The relief thus obtained may be partial or complete depending on the relative dimensions of the inductance, and the capacity. To make this point perfectly clear, consider a circuit containing in series an inductance (L) and a capacity (C), a resistance (R) and a generator having an electromotive force $E \sin pt$. In such a circuit the reactance of the inductance is pL . The reactance of the capacity is

$$\frac{1}{pC}$$

These two reactances being in phase opposition, the total net reactance of the circuit is given by

$$(1) \quad \text{Reactance} = pL - \frac{1}{pC}$$

Clearly, then, there is a frequency for which the two reactances, the capacity reactance and the inductive reactance, are equal to each other, and the net reactance is equal to zero.

Where, however, a number of frequencies have to be transmitted simultaneously, which is the general case in signalling circuits, both wire and wireless, the difficulty arises that if the signalling circuit is tuned to some one frequency, all other frequencies are adversely affected.

This invention relates to the discovery of a method for obtaining what can be properly called a "negative" inductance. Full disclosure is made herein of the means required to carry out the method. Essentially, according to our definition of it, a "negative" inductance is a device which, in its effect, when interposed in an electrical circuit, is the exact counterpart of an ordinary inductance for

the entire range of frequencies from practically zero to practically infinity.

The reactance of an ordinary inductance is expressed by the relation:

$$(2) \quad \text{Reactance of ordinary inductance} = 55 \\ + pL.$$

The corresponding reactance of the device first disclosed in these specifications designated herein as "negative inductance" may be expressed by:

$$(3) \quad \text{Reactance of "negative inductance"} = 60 \\ = -pL.$$

Assuming such a "negative inductance" ($-pL$) to have been wired in series with an ordinary inductance ($+pL$) in an electrical circuit, wherein acts an electromotive force of frequency (p), it follows immediately that the net reactance in this circuit is equal to

$$(4) \quad pL - pL = 0. \quad 65$$

Hence in such a circuit, if a number of electromotive forces having different frequencies (instead of a single frequency electromotive force) were active, the reactance of the circuit would be uniformly zero for all frequencies as shown by Equation (4). There would be no discrimination as between different frequencies. To put this in another way, we would have realized a distortionless circuit. This is obviously true, since the above relation holds regardless of (p).

The practical importance, in signalling work of a "negative" inductance, having the characteristics hereinabove outlined, is too evident to require further comment.

It should be understood, of course, that instead of complete neutralization of the positive inductance of the circuit, we may arrange for partial neutralization, if we so wish. The "relative" neutralization in such a case will be the same for all frequencies. If, for instance, we wish 50% neutralization of the positive inductance (pL) in the circuit, then the combination of the positive inductance and of the "negative" inductance will be represented by

$$\left(\frac{pL}{2}\right).$$

It is necessary and sufficient in order to real- 100

ize the above purpose that the value of the negative inductance be equal to

$$5 \quad \left(\frac{-L}{2} \right).$$

The reactance of the series combination is thus given by:

$$10 \quad pL - \frac{pL}{2} = \frac{pL}{2}.$$

The important point to note is this—that while neutralization of inductance reactance is also possible through the use of ordinary capacity, such neutralization is not equally effective for all frequencies. If it is 100% at some one frequency—so that for this frequency the net reactance is zero—it will be 25% only for double frequency. This is evident, since, if series capacity is used for neutralization purposes, the net reactance of the circuit is given by:

$$\text{Net reactance} = pL - \frac{1}{pC}.$$

25 If as stated, for some definite frequency the above reactance is equal to zero, then:

$$pL = \frac{1}{pC}$$

30 Now, for double the above frequency, the first term in the above reactance equation, is twice as large, while the second term is numerically only one-half in value. Assume that for the original frequency the positive reactance (pL) is 1000 ohms, the negative reactance is now, for double frequency 500 ohms. Therefore, the net reactance is (2000—500) ohms or only 1500 ohms. The neutralization which was 100% for the frequency as originally assumed is now only 25% for double frequency. This brief description gives a clear idea of the "distortion" that is produced when capacity reactance is used in series with an inductance. 40 It also gives a clear picture of the great value of "negative" inductance, as herein disclosed, since neutralization is in the same proportion for all frequencies when "negative" inductance is used to balance out in part a positive inductance in an electrical network. 45

The discussion given above for series neutralization of the positive reactance of an inductance by means of "negative" inductance as compared with similar neutralization by means of capacity also holds true for parallel neutralization, or parallel use of "negative" inductance with positive inductance.

50 The method I have discovered to realize the object of this invention is briefly, to use in parallel with a negative resistance a series combination comprising an ordinary positive resistance having the same absolute value as the negative resistance and a capacity. The value of the capacity used is to be chosen in accordance with the rules indicated below.

The novel features of my invention are pointed out in the appended claims. The invention itself will be best understood by reference to the drawing and the discussion given hereunder.

Fig. 1 of the drawings shows the general idea underlying the use of my method. Fig. 2 shows a particular method of carrying out my invention, using as a negative resistance the particular type of circuit and apparatus covered in U. S. A. Patent No. 1,606,350, granted to me. Fig. 3 shows in graphic form the characteristics of the "negative" inductance device as a function of frequency. As a matter of interest, the characteristics of an ordinary capacity are also shown in this same figure in dotted line. It will be seen at a glance how different the two are. In the case of the "negative inductance" of the present specifications, the absolute value of the negative inductance increases as the frequency increases, while for an ordinary capacity the opposite trend holds. Furthermore the reactance variation is directly proportional to frequency, while in the case of ordinary capacity it is inversely proportional to the frequency.

The arrangement of apparatus shown on Fig. 1 of the drawing across terminals (1, 2) represents a "negative inductance" within the meaning already specified. Element 3 is an ordinary resistance. Element 4 is a negative resistance. It may be of any type known to the art. It may be of the type first disclosed by Dr. Hull (U. S. A. Patent, 1,313,188), or preferably, it may be of the type first disclosed by me (U. S. A. Patent 1,606,350) and reproduced in Fig. 2 of the drawing wired across terminals 7 and 8.

To show how effectively the combination realizes the requirements for a negative inductance, as defined above, consider the mathematical expression for the impedance of the parallel combination of elements 4, 5 and 6. Using the usual imaginary notation, the expression is given by

$$100 \quad (5) \quad \frac{-R\left(R - \frac{j}{pC}\right)}{-R + R - \frac{j}{pC}} = \frac{-R\left(R - \frac{j}{pC}\right)}{-j - \frac{j}{pC}}$$

105 where j is the usual imaginary vector $\sqrt{-1}$. Bearing in mind that $j^2 = -1$, we obtain after multiplying the numerator and the denominator of the above expression for the parallel impedance of elements 4, 5 and 6, by $(+j) -$

110 (6) Parallel impedance =

$$115 \quad \frac{-jR\left(R - \frac{j}{pC}\right)}{\frac{1}{pC}} = -R - j\frac{R^2}{pC}$$

120 The first term of the above expression is a negative resistance. The second or imaginary term represents a "negative" reactance,

and is of opposite sign to the positive reactance of an inductance. Furthermore it can be written in the form:

$$5 \quad \frac{-jR^2}{\frac{1}{pC}} = -jp(R^2C)$$

It is seen, from the expression as just written, that the reactance of this new device is 10 directly proportional to (p), the frequency factor, just as in the case of an ordinary inductance. But, it has the opposite sign ($-$), instead of the positive sign ($+$), which is the sign assumed in these specifications for the 15 reactance of an ordinary inductance. Now (R) and (C) in the above expression are practically anything we choose. We can therefore, if we wish to secure a "negative" inductance of predetermined value ($-L$), so 20 choose the above values of (R) and (C) that

$$(7) \quad L = CR^2$$

We can secure therefore the value of the element (6) of the drawing from fundamental Equation (7). It should be noted that R is still indeterminate and may be best chosen so as to secure convenient or practical values for the capacity (C) required to realize a negative reactance.

30 Once we have determined the value of (C), as just described, we can write as follows the value of the parallel impedance of elements (4) (5) and (6).

$$35 \quad (8) \quad \text{Parallel impedance} = -R - jpL.$$

The combination of element 3 (series positive resistance R) with the parallel impedance of elements 4, 5 and 6 as just written has an impedance equal to

$$40 \quad (9) \quad R - R - jpL = -jpL.$$

The impedance of the combination of apparatus connected to terminals (1) and (2) of the drawing, is therefore given by ($-pL$), a 45 "negative inductance" in the true sense of the term. This entirely new device in the art, no matter what the frequency factor (p) acts exactly like an inductance, so far as frequency variation is concerned, but otherwise is in 50 exact phase opposition.

If, in an electric circuit, we have an inductance (L), the combination of apparatus indicated on Fig. 1 of the drawing used in series with this inductance will wipe out completely the reactance effect of this inductance, regardless of the frequency of the current which may be transmitted through such a circuit if the constants of the circuit have been chosen as indicated to obtain a value of 60 ($-L$) for the negative inductance.

A very valuable advantage of the arrangement shown on the drawing is the ease with which the value of the negative inductance may be changed. To obtain a change it is 65 sufficient to change the value of the resistance

elements shown on Fig. 1 or Fig. 2, without changing the condenser or capacity element (6). All the resistance elements must be changed the same amount. If the various resistance elements have been changed, say 70 10%, the inductance will have changed with the square of said change, or 1.21. This will be clear by reference to formula (7). Or we may leave the resistance elements alone, and change only the value of condenser (6). In 75 this case, the variation of the value of the negative inductance is directly proportional to the variation in the value of the capacity of element (6).

I claim:

1. An automatic device having reactance characteristics of opposite sign to that of an inductance, such reactance varying in direct proportion with frequency, in accordance with the formula:

$$80 \quad \text{Reactance} = -2\pi f(L)$$

where (f) is the frequency and (L) is a constant.

2. A two-terminal network consisting of 90 the combination of a negative resistance in parallel with a positive resistance and a condenser in series, said parallel combination being wired in series with a positive resistance, all three resistances being substantially 95 equal in absolute value.

3. An automatic device having reactance characteristics of opposite sign to that of an inductance, such reactance varying in direct proportion with frequency, with additional 100 means for varying the value of said reactance in equal proportion for all frequencies.

4. In an electric network containing an inductance, automatic means for the partial neutralization of said inductance to the flow 105 of currents through said network, equally effective for all frequencies.

5. In an electric network for the simultaneous transmission of a band of frequencies, containing an inductance, automatic 110 means for the complete neutralization of said inductance to the flow of currents through said network, equally effective for all frequencies.

6. In an electric circuit containing an inductance, automatic means for neutralizing the effect of said inductance to the flow of current through said circuit, such means being 115 equally effective at all frequencies.

In testimony whereof I affix my signature. 120
MIHRAN M. DOLMAGE.
